UNITED STATES PATENT OFFICE

145,962

DESIGN FOR A WOOD PLANE

Felix J. Zagumny, Detroit, Mich., assignor to John A. Maxwell & Associates, Detroit, Mich., a partnership consisting of John A. Maxwell and Murray M. Taylor

Application June 4, 1945, Serial No. 119,897

Term of patent 14 years

(Cl. D93—4)

To all whom it may concern:

Be it known that I, Felix J. Zagumny, a citizen of the United States, residing at Detroit, in the county of Wayne and State of Michigan, have invented a new, original, and ornamental Design for a Wood Plane, of which the following is a specification, reference being had to the accompanying drawing, forming part thereof.

Figure 1 is a perspective view of a wood plane showing my new design; and

Figure 2 is a sectional view taken on line 2—2 of Figure 1.

I claim:

The ornamental design for a wood plane, as shown.

FELIX J. ZAGUMNY.
